(57) **CLAIM**

I claim the ornamental design for a pot, trivet, and lid set, as shown and described.

DESCRIPTION

FIG. 1 is a perspective view of a pot, trivet, and lid set, showing my new design in a first embodiment;
FIG. 2 is a top view thereof;
FIG. 3 is a left side view thereof;
FIG. 4 is a front view thereof;
FIG. 5 is a right side view thereof;
FIG. 6 is a rear view thereof;
FIG. 7 is a bottom view thereof;
FIG. 8 is a perspective view of the pot, trivet, and lid set, with the lid and pot shown separately to show aspects of the design that are not visible when combined;
FIG. 9 is a top view thereof;
FIG. 10 is a left side view thereof;
FIG. 11 is a front view thereof;
FIG. 12 is a right side view thereof;
FIG. 13 is a rear view thereof;
FIG. 14 is a bottom view thereof;
FIG. 15 is a perspective view of the pot, trivet, and lid set, showing my new design in a second embodiment;
FIG. 16 is a top view thereof;
FIG. 17 is a left side view thereof;
FIG. 18 is a front view thereof;
FIG. 19 is a right side view thereof;
FIG. 20 is a rear view thereof;
FIG. 21 is a bottom view thereof;
FIG. 22 is a perspective view of the second embodiment of the pot, trivet, and lid set, with the lid and pot shown separately to show aspects of the design that are not visible when combined;
FIG. 23 is a top view thereof;
FIG. 24 is a left side view thereof;
FIG. 25 is a front view thereof;
FIG. 26 is a right side view thereof;
FIG. 27 is a rear view thereof;
FIG. 28 is a bottom view thereof;
FIG. 29 is a perspective view of the pot, trivet, and lid set, showing my new design in a third embodiment;
FIG. 30 is a top view thereof;
FIG. 31 is a left side view thereof;
FIG. 32 is a front view thereof;
FIG. 33 is a right side view thereof;
FIG. 34 is a rear view thereof;
(Continued)

FIG. 35 is a bottom view thereof;
 FIG. 36 is a perspective view of the third embodiment of the pot, trivet, and lid set, with the lid and pot shown separately to show aspects of the design that are not visible when combined;
 FIG. 37 is a top view thereof;
 FIG. 38 is a left side view thereof;
 FIG. 39 is a front view thereof;
 FIG. 40 is a right side view thereof;
 FIG. 41 is a rear view thereof; and,
 FIG. 42 is and bottom view thereof.
 The broken lines in the figures depict portions of the pot, trivet, and lid set that form no part of the claimed design.
